(57) **CLAIM**

The ornamental design for an alpha star cross omega design, as shown and described.

DESCRIPTION

FIG. 1 is a front elevational view of an alpha star cross omega design showing my design;

FIG. 2 is a perspective view of a second embodiment of an alpha star cross omega design showing my new design;

FIG. 3 is a front elevational view of FIG. 2;

FIG. 4 is a bottom plan view of FIG. 2;

FIG. 5 is a top plan view of FIG. 2;

FIG. 6 is a right side elevational view of FIG. 2;

FIG. 7 is a left side elevational view of FIG. 2;

FIG. 8 is a rear elevational view of FIG. 2;

FIG. 9 is a perspective view of the first embodiment, FIG. 1, shown in a position of use;

FIG. 10 is a front elevational view of FIG. 1, shown in a position of use;

FIG. 11 is a bottom plan view of FIG. 10;

FIG. 12 is a top plan view of FIG. 10;

FIG. 13 is a right side elevational view of FIG. 10;

FIG. 14 is a left side elevational view of FIG. 10; and,

FIG. 15 is a rear elevational view of FIG. 10.

Broken lines are used in the Figures to indicate portions of a jewelry article that does not form part of the claimed design.
